(57) **CLAIM**

The ornamental design for a disposable male canine wrap, as shown and described.

DESCRIPTION

FIG. 1 is a perspective view of a disposable male canine wrap embodying my design;

FIG. 2 is a front view of the disposable male canine wrap;

FIG. 3 is a rear view of the disposable male canine wrap;

FIG. 4 is a right side view of the disposable male canine wrap;

FIG. 5 is a left side view of the disposable male canine wrap;

FIG. 6 is a top view of the disposable male canine wrap; and,

FIG. 7 is a bottom view of the disposable male canine wrap.

1 Claim, 5 Drawing Sheets(56)
